UNITED STATES PATENT OFFICE

JUANITA TODD, OF YONKERS, NEW YORK, ASSIGNOR TO SIDNEY BLUMENTHAL & CO., INC., OF NEW YORK, N. Y., A CORPORATION OF NEW YORK

DESIGN FOR A PILE FABRIC RUG

Application filed November 18, 1931. Serial No. 41,773. Term of patent 3½ years.

To all whom it may concern:

Be it known that I, JUANITA TODD, a citizen of the United States of America, and resident of the city of Yonkers, in the county of Westchester and State of New York, have invented a new, original, and ornamental Design for a Pile Fabric Rug, of which the following is a specification, reference being had to the accompanying drawing, forming part thereof.

The figure is a plan view of a pile fabric rug showing my new design.

I claim:

The ornamental design for a pile fabric rug substantially as shown.

JUANITA TODD.
